(57) **CLAIM**

The ornamental design for a jewelry connector system with
interchangeable charms, as shown and described.

DESCRIPTION

FIG. 1 is a top perspective view of a jewelry connector
system with interchangeable charms, showing my new
design in a state of use;

FIG. 2 is a bottom perspective view thereof, showing the
jewelry connector system of FIG. 1 in a state of use and
without the cover pad element, to show aspects of the design
that are not visible when combined;

FIG. 3 is another bottom perspective view thereof, showing
the jewelry connector system of FIG. 1 in a state of use;

FIG. 4 is an enlarged front perspective view thereof;

FIG. 5 is an exploded front perspective view thereof;

FIG. 6 is a front elevational view thereof;

FIG. 7 is an exploded rear elevational view thereof;

FIG. 8 is a rear elevational view thereof;

FIG. 9 is a top plan view thereof;

FIG. 10 is a bottom plan view thereof;

FIG. 11 is a left-side elevational view thereof; and,

FIG. 12 is a right-side elevational view thereof.

The broken lines represent portions of the jewelry connector
system with interchangeable charms and form no part of the
claimed design. The other broken lines in FIGS. 1, 2, and 3
showing a hat represent environmental subject matter only,
and form no part of the claimed design.
